UNITED STATES PATENT OFFICE.

JAMES W. BROOKS AND JOHN H. KINEALY, OF FERGUSON, MISSOURI.

SHEET TO BE USED FOR PRINTING PUBLICATIONS.

No. 883,157.

Specification of Letters Patent. Patented March 24, 1908.

Application filed November 5, 1906. Serial No. 342,065.

To all whom it may concern:

Be it known that we, JAMES W. BROOKS and JOHN H. KINEALY, both residing at Ferguson, in the county of St. Louis and State of Missouri, have invented a new and useful Improvement in Sheets to be Used for Printing Publications, of which the following is a full, clear, and exact specification, reference being had to the accompanying drawings, which 10 form a part thereof.

Our invention relates to sheets of paper which are used for printed publications, printing on both sides of the sheets the pages that are to appear in the publication; said 15 pages being arranged so that when the sheets are folded they will follow one another according to a certain predetermined order.

The object of our invention is to enable publishers to provide at low cost, illustrations for advertising matter which is to appear in the pages of their publications; and another object of our invention is to enable 20 advertisers who advertise only at irregular intervals to obtain illustrations for the matter of their advertisements without the necessity of having special cuts prepared, thus enabling the advertisers to add to the effectiveness of the texts of their advertising matter.

The figures show a form of our invention in 25 which a sheet of paper is used in such a way as to form, when properly folded, four pages of a publication.

Figure 1 shows the side of the sheet that will appear as pages 1 and 4 of the publication; and Fig. 2 shows the side of the sheet that will appear as pages 2 and 3 of the publication.

The publishers of what are known throughout the country as local magazines, are in the 40 habit of buying a certain number of pages of printed matter for the magazine containing stories and other matter of interest, and which in the trade is known as syndicate matter. This syndicate matter in connection with local matter, which is matter pertaining to the localities in which the magazines are published, form the complete magazine. The local publisher derives his income 45 from the sales of advertising space to merchants, manufacturers, and others who wish to reach the people in the special locality where the magazine circulates. The firm furnishing the syndicate matter derives its income from the sale of the syndicate matter to 50 the publishers and also from the sale of advertising space to what are known as national

advertisers. The publisher after buying the syndicate matter buys ordinary white paper sheets on which he prints all the pages of the local matter of the magazine and also all the 60 pages devoted to local advertisers. As the local advertisers cannot usually afford to have cuts made for the purpose of illustrating the texts of their advertisements, the section of the magazine devoted to local advertisers 65 does not present so attractive an appearance as that devoted to the national advertisers, because of the absence of illustrations in connection with the advertisements of the local section. In our invention sheets of paper 70 are prepared by printing upon them illustrations suitable to such local standard businesses as are likely to be advertised in the local sections of the magazines and then the local publisher simply prints upon these prepared sheets the text of each local advertisement in such a way that it will appear in connection with, and as complementary to, a proper and suitable illustration. This enables the publisher to provide at a small cost 75 suitable illustrations for the local advertising matter and enables him to make his advertising space more attractive and easily sold to the local advertiser; and it further enhances the drawing or "pulling" power of the local advertisement, and enables the local advertiser to obtain greater returns from it than he otherwise would. It also makes the pages devoted to local advertisements have a better 80 appearance and be more in keeping with the pages devoted to national advertisements, than if plain sheets of paper were used instead of the prepared sheets.

In the drawings, the line along which the sheet of paper is to be folded in order to form 85 the pages is indicated by the dotted line A B. The number of each page is indicated by the numeral written in the upper corner of the page, and each page has at the top the word "Advertisements" to indicate that it is devoted to advertising matter.

C represents an illustration for an advertisement; D represents the space in which the text of the advertisement will be printed; and E represents a border by which the illustration and the printed matter are connected or inclosed. As prepared for sale to the publisher, the sheets will have upon them the illustrations C, and the borders E, but the printed matter in the space D is to be printed in by the publisher of the magazine.

In Fig. 1, the upper half of page 1 is sup-

posed to be set apart for the advertisement of a firm selling such dress goods as are sold by dry goods establishments. The lower left hand quarter of this same page is supposed to be devoted to the advertisement of a grocery store. The lower right hand quarter of this page has only an illustrated border and is supposed to be used for an advertisement for which no special illustration is required. The left hand half of page 4 is supposed to be devoted to an advertisement of a hardware store, and the upper right hand quarter is supposed to be used for an advertisement of a drug store. The lower right hand quarter of this page is supposed to be used by a baker or confectioner.

In Fig. 2, page 2 contains in the upper quarter a space suitable for the advertisement of a boot and shoe dealer; and in the middle half a space suitable for the advertisement of a real estate dealer or a builder. The lower quarter of this page is divided into two spaces, each of which is supposed to be one-eighth of a page and has only an illustrated border so that it is suitable for any small advertisement. Page 3 in Fig. 2 shows one whole page which is supposed to be devoted to the advertisement of a dry goods store, and has an illustration intended to supplement the text of the advertisement.

The figures show some of the different ways in which a page may be divided and also the character of the illustrations that may be used in connection with the spaces. It is evident that the number of pages that may be made of one sheet may be varied at will, and depends only upon the relative sizes of the sheet of paper and the pages of the publication. The character and general appearance of the illustrations may be varied and made so as to best serve the purpose and demands of the local advertisers.

What we claim as new and desire to secure Letters Patent for, is:

1. A sheet of paper to be used for printing publications, having illustrations thereon suggestive of different businesses, and having spaces adjacent to said illustrations free from printed matter and of sufficient dimensions to receive the necessary advertising matter relating to the subject matter of said illustrations, substantially as described.

2. A sheet of paper to be used for printing publications, having illustrations thereon suggestive of different businesses, and having spaces adjacent to said illustrations free from printed matter and of sufficient dimensions to receive the necessary advertising matter relating to the subject matter of said illustrations, and having borders identifying said spaces with their respective illustrations, substantially as described.

3. A sheet of paper to be used for printing publications, having illustrations thereon suggestive of different businesses, each of which is illustrative of some phase of the business which it suggests, and having spaces adjacent to said illustrations free from printed matter and of sufficient dimensions to receive the necessary advertising matter relating to the subject matter of said illustrations, substantially as described.

4. A sheet of paper to be used for printing publications, having illustrations thereon suggestive of different businesses, and having spaces adjacent to said illustrations free from printed matter and of sufficient dimensions to receive the necessary advertising matter relating to the subject matter of said illustrations, said illustrations and spaces being positioned to appear on the pages of the publication when said sheet is folded, substantially as described.

5. A sheet of paper to be used for printing publications, having illustrations thereon suggestive of different businesses, and having spaces adjacent to said illustrations free from printed matter and of sufficient dimensions to receive the necessary advertising matter relating to the subject matter of said illustrations, and borders identifying said spaces with their respective illustrations, the illustrations and spaces being positioned to appear on the pages of the publication when said sheet is folded, substantially as described.

In testimony whereof we affix our signatures, in the presence of two witnesses.

JAMES W. BROOKS.
JOHN H. KINEALY.
